METHOD OF AND APPARATUS FOR SOUND RECORDING

Max C. Batsel, Haddonfield, N. J., assignor to
Radio Corporation of America, a corporation
of Delaware

Application December 30, 1938, Serial No. 248,394

2 Claims. (Cl. 179—100.3)

This invention relates to a method of and apparatus for recording sound by what is known as the variable density method, and more particularly to the species thereof known as "squeeze track" recording. Squeeze track recording is known in the prior art in the form of apparatus where masks are inserted in the light beam to limit the effective track width in variable density recording. Such apparatus is subject to certain practical limitations due to the fact that the operator thereof is not always able to accurately forecast the track width necessary, and, also, the adjustment of changes in track width are necessarily more or less abrupt.

According to the present invention, I maintain the amplitude of the signal applied to the recording galvanometer or equivalent light control apparatus substantially constant, and vary the track width by means of electrically controlled shutters in proportion to the loudness of the sound. In the recording, the volume of the recorded sound is controlled automatically to bring it to a constant average level, while the track width control shutters are operated in a manner complementary to the operation of the volume control so that when the volume of loud sounds is decreased to bring them to the constant amplitude, the track width control shutters are moved apart a corresponding amount to provide increased available volume on the sound recording, and conversely when a relatively soft sound is amplified to bring it up to average level, the shutters are moved toward each other to give a lessened track width.

The invention, of course, is not limited to the use of a perfectly constant average amplitude of modulation of the galvanometer or equivalent device nor to the use of two shutters. A single shutter or modified shapes of shutters, such as are well known in the art, may be used to produce the desired control of track width. The volume control, and the corresponding shutter control may be accomplished with any desired degree of linearity or non-linearity in relation to the amplitude of the sound.

Likewise the invention is not limited to the regulation of a volume control shutter in a direct relation with the recorded volume, but the shutter may be caused to move a greater or less amount than that which would be proportional to the volume changes in the recorded sound, thereby producing either volume expansion or volume compression.

One object of the invention is to provide an improved apparatus for variable density sound recording.

Another object of the invention is to provide an improved method for variable density sound recording.

Another object of the invention is to provide a

method of and apparatus for variable density sound recording in which the volume level of the recorded sound may be maintained constant or in any desired ratio to the volume range of the sound recorded.

Another object of the invention is to provide an improved apparatus for recording sound by what is known as the penumbra method.

Another object of my invention is to provide an improved apparatus for producing what is known as a squeeze sound track record.

Other and incidental objects of my invention will be apparent to those skilled in the art from a reading of the following specification and an inspection of the accompanying drawing in which

Figure 1 is a schematic diagram of my improved apparatus showing portions of the optical system thereof in perspective.

Figure 2 is a schematic diagram showing a modified form of the invention, and

Figure 3 is a plan view of the optical system used in the apparatus.

Referring first to Fig. 1, which shows the preferred form of the invention, the sound to be recorded is impressed on the microphone indicated at 10 and is transmitted to the amplifier 11. This amplifier may be of any customary type such as those usually used in sound recording. The audio frequency output from the amplifier 11 is transmitted to the automatic volume control device 13. This device is not shown in detail as automatic volume controls are well known in the art and are customary in radio receivers and similar devices. This automatic volume control brings the electrical impulses corresponding to the sounds to a substantially constant average value. If desired, this volume control device may, instead of bringing the sounds to a uniform average value, merely reduce the range of their volume to within predetermined limits or in a predetermined ratio to the loudness of the original sounds, the essential feature being that it will materially decrease the volume range of the output impulses as compared with the volume range of the sounds impressed upon the microphone 10. The output from the AVC device 13 is transmitted to a galvanometer 12 having a mirror 25 adapted to be vibrated in accordance with the acoustic impulses transmitted to the galvanometer.

A portion of the output from the amplifier 11 is transmitted to the ground noise reduction amplifier 14. This amplifier is referred to as a ground noise reduction amplifier because it is of the same type as generally used for ground noise reduction in sound recording and it produces an output current which is unidirectional and which varies in amplitude in accordance with the envelope of the electrical impulses corresponding to sound waves impressed on the amplifier. This

correspondence may be either direct or inverse, depending on the manner in which the amplifier is connected. An example of such an amplifier circuit is shown in McDowell Patent 1,855,197. 5 The output from the amplifier 14 is directed to the magnet or magnets 15 of the shutters 16 and 17.

The optical system used as shown in Figs. 1 and 3 is preferably of the "penumbra" type for 10 variable density recording such as described on pages 270-273 of the Journal of the Society of Motion Picture Engineers for September 1937. In this optical system, light from the exciter lamp 20 passes through the cylindrical lens 21 and the spherical lens 22 to the penumbra aperture 23, adjacent which an image of the filament of the lamp 20 is formed in such relation as to provide a graduated illumination of the aperture in the plate 23. An image of the aperture in the 15 plate 23 is formed upon the slit plate 26 by the lens 24, the light being reflected from the galvanometer mirror 25 by which it is vibrated in accordance with the sound waves. A condenser lens 30 is provided adjacent the slit plate 26 for 20 increasing the illumination transmitted therethrough.

Between the lens 21 and 22 and the aperture plate 23 there is provided an aperture plate 29 adjacent to which are located the shutters 16 and 30 17 actuated by the magnetic means 15 from the amplifier 14. These shutters move transversely across the aperture in the plate 29 in accordance with the volume of the sound as above described, thereby varying the width of the image formed 35 upon the slit plate 26. The objective lens 27 focuses a linear image of the light passing through the slit plate 27 upon the film 28. The preferred type of shutter mechanism is described in detail and is claimed in Hasbrouck Patent 2,102,778, issued December 21, 1937.

The amplifier 14 is so connected to the shutter mechanism 15, 16, 17 that when the amplitude of the sounds to be recorded decreases, the shutters are moved toward each other or if a single shutter or a V-shaped shutter were used, the shutter 45 would be moved correspondingly toward a position where the sound track width would be a minimum, thereby decreasing the sound track width in appropriate ratio to the decrease in amplitude of the sound. As pointed out above, this movement of the shutters may be so chosen as to give volume compression or volume expansion or to merely control the sound track width directly in accordance with the volume range. It will be 50 apparent that this change in sound track width varies proportionately the amount of light transmitted thereto in recording and accordingly the amount of light transmitted therethrough in reproduction of a positive print.

The foregoing arrangement permits the density 55 modulation of the sound track in accordance with the sound frequencies to be maintained at an optimum value or between desired limits producing the most desirable values of exposure in the recording, while at the same time providing adequate volume range. The arrangement further may substantially eliminate manual volume control during recording.

If desired, additional noise reduction may be 60 accomplished by the usual method of keeping the

sound track density as high as feasible for the amplitude of the sound waves being recorded. Such procedure does not in any way interfere with the construction or operation of the apparatus.

If it is desired to control the apparatus manually instead of automatically, the arrangement shown in Fig. 2 may be used.

In this arrangement the microphone 10 and main amplifier 11 are provided as in the first arrangement, but attenuator 32 is substituted for the automatic volume control 13. This attenuator, like the automatic volume control, lowers the impulses from the amplifier 11 to the galvanometer 12 to a predetermined level but instead of this level being fixed, it may be manually adjusted by means of a control knob 35. If the sound to be recorded is expected to be very low in level, the knob is so adjusted as to give very little attenuation, or if the sound is expected to be very high in level, the attenuator is adjusted to give considerable attenuation. In order to operate the shutter mechanism 15, an appropriate source of power such as the battery 33 is provided together with a control means, such as a 25 potentiometer 34. A series resistor, of course, may be substituted if desired for the potentiometer. In either event, the control means 34 serves to control the current through the magnets of the shutters 16 and 17, thereby determining the 30 track width to be used. As indicated in the drawing, the attenuator 32 is interconnected with the shutter control 34 so that at any degree of attenuation an inversely corresponding track width is provided. If loud sounds are being recorded 35 they are considerably attenuated and a relatively large track width is used, and conversely on faint sounds the attenuation is very slight, but a narrow track is used.

It will be apparent to those skilled in the art that in either of the above described arrangements the sound track width is controlled in proportion to the volume of the sounds being recorded, while the sound volumes as applied to the recording galvanometer are reduced to a more or less uniform level and that in both cases the variation in sound track width is maintained in a predetermined ratio to the variation in amplitude transmitted to the galvanometer.

Having now described my invention, I claim:

1. A sound recording apparatus including 50 means for producing a variable density sound record at a constant amplitude level from impulses at varying amplitude levels, and means for controlling the area of said record in accordance with the envelope of said impulses at varying amplitude levels, said means including shutters movable inwardly from the edges of the record.

2. A sound recording apparatus including an 55 amplifier, automatic volume control means for maintaining the output of said amplifier at a substantially constant level, means for recording said constant level output as a variable density record, and independent means including shutters movable inwardly from the edges of the record controlled by the output of said amplifier for controlling the area of said record in accordance with the output of said amplifier.

MAX C. BATSEL.
